(57) **CLAIM**

The ornamental design for a center console for an automobile, as shown and described.

DESCRIPTION

FIG. 1 is a front elevational view of a center console for an automobile in accordance with our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a first perspective view thereof; and,

FIG. 8 is a second perspective view thereof.

The center console is configured to be mounted to an automobile. The inside surfaces of the center console, shown in broken lines in FIGS. 1 to 8, form no part of the claimed design since the inside surfaces are hidden when the center console is mounted to the automobile.

A second embodiment of my new design includes the mirror image of the center console shown in FIGS. 1 to 8.
